UNITED STATES PATENT OFFICE.

WILLIAM ALFRED PIKE, OF MEDFORD, MASSACHUSETTS.

PIPE-VISE SUPPORT.

1,111,032.

Specification of Letters Patent. Patented Sept. 22, 1914.

Application filed May 17, 1913. Serial No. 768,227.

To all whom it may concern:

Be it known that I, WILLIAM A. PIKE, of Medford, in the county of Middlesex and Commonwealth of Massachusetts, a citizen 5 of the United States, have invented certain new and useful Improvements in Pipe-Vise Supports, of which the following is a full and exact description.

One of the time-consuming difficulties to 10 which plumbers are exposed is that of cutting and threading gas and other piping in old and finished buildings. As it is out of the question for them to bolt their pipe-clamps to finished wood work, they are 15 obliged to tramp up or down stairs to the cellar or attic where places can be secured for the attachment of the pipe-clamps.

The object of this invention is the construction of a pipe-clamp support which can 20 be fastened securely to doors, door frames and other suitable finished wood work, without danger of marring the same in the slightest degree.

Referring to the drawings forming part 25 of this specification, Figure 1 is a perspective view of a pipe-clamp and its support made in accordance with my invention, the same being shown fastened to a suitable object. Fig. 2 is a perspective view of parts of 30 said support viewed from a direction opposite to that of Fig. 1. Fig. 3 is a detail view illustrating the locking device for the adjustable member. Fig. 4 is another view of said device. Fig. 5 is a top or edge view of 35 the movable clamping member. Fig. 6 is a view of a modification of the invention for enabling the support to be fastened to a cylindrical post or bar.

The object selected for illustration in Fig. 40 1 for the attachment of my pipe-clamp support may be imagined to be a portion of the framing of a door way, or even the free edge of a heavy door. The pipe-clamp 1 is of a usual and well known type, and forms no 45 part of the invention, the same being shown in Fig. 1 in order better to illustrate the method of using the support. The support being most frequently attached to a vertical object, as the door frame 2, I shall describe 50 the parts composing the same as though the positions disclosed in the drawings were their exclusive ones.

The main member of the support comprises the upright 3 formed with two ex- 55 posed faces 4 and 5 at right angles to each other and each formed with similar slots 6

for receiving the fastening bolts with which the elbow 7 of the pipe-clamp is provided; said upright being formed with said two faces for the purpose of permitting the pipe-clamp to be fastened to one or the other thereof so that the pipe to be operated upon can be extended either through the doorway, or parallel with the wall, depending upon which proves to be the more convenient to the plumbers. Horizontally from said upright projects a clamping arm 9 recessed for the reception of pads 10 preferably of leather, as indicated in Fig. 2, and designed to contact with one surface of the object 2. At right angles to the surface 4 extends a bar 11 notched along one edge and slidably carrying a clamping member for coacting with said clamping arm 9. Said clamping member comprises a sleeve 12 having an arm 13 carrying a clamping screw 14 at whose end is a plate 15 provided with a pad 16 (Fig. 5). By turning said screw until its padded plate 15 is set against the surface of the object 2 with sufficient force, the support is fastened securely in place.

To prevent the support from rocking, small padded plates 17 (Fig. 2) are provided at the ends of the upright 3, adapted to be set up against the front face of the object 2 by means of thumb screws 19, as shown in Fig. 1.

Ordinarily, the above described clamping means for the support are ample, but occasionally for the threading or cutting of extra large and heavy piping, additional bracing is needed. For such purpose, the sleeve 20 is provided having a socket 21 snugly receiving a vertical rod or pipe 22 fixed therein by a set screw 23, said sleeve slidable on said bar 11. Parallel with said bar 11 is a similar bar 24 carrying a sleeve 25 having a socket 26 receiving said rod 22; a set screw 27 fixing the latter in place in said socket. At one end of the bar 24 is a padded arm 29 rigid therewith and designed to press against the same surface of the object 2 as does the arm 9. Slidable on the bar 24 is a second sleeve 30 carrying a set screw 31 provided with a clamping plate 32 suitably padded, similar to that shown in Fig. 5. Said bar 24 is formed with notches 33 like those in the bar 11 and for the same purpose,—that of locking the sleeve 30 at any one of numerous points. The device for engaging said notches 110 consists of a wire loop 34 having its terminals turning in the ear 35 projecting from a

sleeve 30, 12. By swinging such loop into a notch and then moving the sleeve back against the loop, as shown in Fig. 3, further pressure against the sleeve is firmly resisted, 5 and the clamping screw can be turned up solidly against the object 2.

In case it is desired to support the vise clamp upon a round post, as 36 in Fig. 6, removable concave padded jaws 37 are applied to the arm 9 and clamping plate 15 and held in place by suitable thumb screws 39.

Thus arranged, the vise clamp can be attached in a moment or two to any suitable supporting object, varying from two or three 15 inches in thickness to a foot or more; it will be firmly supported, and when it is removed therefrom it will be found not to have dented or otherwise marred the surfaces of such object, no matter how highly finished the same 20 may have been.

As shown in Fig. 2, the bar 11 is removably held in the socket 40 of the upright 3 by means of a thumb screw 41, in order that the bar can be withdrawn therefrom and 25 the parts packed snugly together for compactness in storage and transportation. To enable the pipe vise to be more readily removed from and applied to the different surfaces of the upright, I provide the vise 30 with T-bolts 42 (Fig. 2) which can be introduced head-first through the slots but after turning half around will remain in place, and withstand all needed strain.

As already stated, the pipe vise can be 35 fastened to either of the two surfaces 4 and 5 of the upright, and so two different positions provided in which the piping can be held; but in addition, by unclamping the support, turning it upside down and applying 40 it to the opposite surface of the object 2, one or two more positions or locations are given for the piping.

My device enables the mechanic to cut and thread his piping close to where he 45 is doing the work. The support can be clamped to a fence, post, table, bench, shelf or even a stove, and to any suitable object in either horizontal, perpendicular or angular position. It will not dent, scratch or 50 mar the finest wood-finish. Moreover, its design is on strong and durable lines. It is of light weight, and can be made of various sizes. For cutting or threading brass piping such as is commonly used in dwellings and offices, and iron piping up to half-inch, it is not necessary for the device to weigh more than three pounds; and for cutting and threading any larger pipe usually cut and threaded by hand, it is not 55 necessary for the complete support to weigh over ten pounds. This light weight, taken in conjunction with its compactness in packing, enables the support to be easily carried by the mechanic in his tool bag. At the 60 same time, it can be taken out from the bag 65 and set up wherever desired in but a moment or two.

It should be noted that this invention does not pertain to the pipe vise, nor is it a pipe vise and clamp combined, but it is simply a 70 support or clamp which enables the user to attach any size or design of vise to any suitable object possessing sufficient strength, no matter what the polish or finish of its surface may be.

What I claim as my invention and for which I desire Letters Patent is as follows to wit:—

1. A pipe vise support comprising an upright having an arm, a bar rigidly extended 80 from the upright at right angles to said arm, a sleeve adjustable along said bar, and a clamping screw carried by said sleeve to oppose said arm, said upright having means for the ready attachment of a pipe vise 85 thereto.

2. A pipe vise support comprising an upright having a padded arm and a bar rigidly extended from the upright at right angles to the padded surface of said arm, a sleeve 90 adjustable along said bar, and a clamping screw carried by said sleeve to oppose said padded surface, said upright having means for the easy attachment of a pipe vise 95 thereto.

3. A pipe vise support comprising an upright having a padded arm and a bar rigidly extended from the upright at right angles to the padded surface of said arm, said bar 100 being notched along an edge, a sleeve slidably mounted on said bar and having an ear, a wire loop pivoted in said ear and adapted to be swung into any one of said notches for locking the sleeve at different 105 points on said bar, and a clamping screw carried by said sleeve to oppose said padded surface, said screw having a padded plate 110 at its operative end.

4. A pipe vise support comprising an upright having two surfaces at right angles to each other, each surface being slotted for receiving the fastening bolts of a pipe vise, an arm rigid with the upright parallel with one of said surfaces, and clamping means 115 opposed to said arm.

5. A pipe vise support comprising an upright having two surfaces at right angles to each other each adapted to have a vise attached thereto, an arm rigid with the upright parallel with one of said surfaces, 120 clamping means connected with the upright for opposing said arm, and clamping devices at the ends of the upright adjustable toward an object between said arm and clamping means.

6. A pipe vise support comprising an upright having a surface adapted to have a pipe vise removably attached thereto, an arm rigid with the upright, a horizontal bar rigid with said upright, a clamping member 125

for opposing said arm adjustable along said bar, a sleeve slidable on said bar and having a vertical socket, a bar parallel with the first named bar, means for clamping the second named bar to the same object as that which may be clamped between the first mentioned clamping means, a sleeve slidable on the second named bar and having a vertical socket, and a vertical rod penetrating both 10 said sockets.

7. A pipe vise support comprising an upright having slots therein and a padded arm

rigid therewith, a clamping device opposing said padded arm, and T-bolts entering said slots for removably attaching a pipe 15 vise to said upright.

In testimony that I claim the foregoing invention, I have hereunto set my hand this 13th day of May, 1913.

WILLIAM ALFRED PIKE.
